TO THE PROSPERITY COMPANY INC., OF SYRACUSE, NEW YORK, A CORPORATION OF
NEW YORK.

PRESSING-MACHINE PLAITING ATTACHMENT.

Application filed May 19, 1926. Serial No. 110,046.

This invention relates to pressing machines, particularly garment pressing machines and has for its object a particularly simple and efficient means for holding the work in a pre-arranged position on the lower pressing element or buck and particularly for holding plaits in a garment after the plaits have been arranged or manipulated prior to the pressing operation.

10 The invention consists in the novel features and in the combinations and constructions hereinafter set forth and claimed.

In describing this invention, reference is had to the accompanying drawing in which 15 like characters designate corresponding parts in all the views.

Figure 1 is a side elevation of a pressing machine embodying my invention.

Figure 2 is a fragmentary plan view of 20 parts seen in Figure 1, the lower pressing element or buck and the contiguous parts of the machine which supports the work holding means being shown.

I have here illustrated my invention as 25 applied to the conventional form of garment pressing machine including upper and lower pressing elements, one of which is movable toward and from the other.

The work holding means includes preferably a plurality of straps arranged to extend transversely across the work on the buck, the straps being secured at their rear ends and having self contained means at their front ends for holding the straps tightly 30 across the work on the buck and thus holding the work or plaits formed in the work preliminary to the pressing operation. Preferably, the straps are shiftable or adjustable lengthwise of the buck.

14 designates the straps which are shown as secured to a rod 15 extending lengthwise of the buck in the rear thereof, this rod be-

ing supported by a back plate 16 which is secured to the frame in the rear of the buck. The straps are slideable along the rod 15 and have loops or eyes 17 through which the rod extends. The rod 15 is arranged below the level of the buck. The means self contained with the straps for holding them tightly across the face of the buck is here shown as weights 18 secured to the front end of the straps. Normally, these straps are entirely in the rear of the buck, the weights resting on the frame of the machine.

When the work is arranged or when the 55 plaits have been arranged by the operator, he draws the first strap over them and owing to the weight 17, the plaits are held as arranged. The operator arranges the plaits from one end toward the other along the 60 buck and as he arranges them, draws a strap over the plaited work to hold the plaits. When the work is completely arranged, the press is operated to bring the head down onto the work and the straps thus permanently forming the plaits.

What we claim is:

A pressing machine comprising upper and lower cooperating pressing elements, one of which is movable toward and from the other, 70 and means for holding the work on the lower element comprising a flexible strap arranged to extend transversely of the lower element, said strap being secured at its rear end and having a weight at its front end.

In testimony whereof, we have hereunto signed our names respectively at Syracuse, in the county of Onondaga, and in the State of New York, this 26th day of April, 1926 and at Syracuse, in the county of Onondaga 80 and in the State of New York, this 13th day of April, 1926.

SERVATIUS ROBERT CHRIST.
PHILIP N. BRAUN.
